[57] ABSTRACT

Colour television display apparatus in which for correction of isotropic astigmatism a correction current flows through the coil halves of at least one deflection coil unit, which current is substantially a square function of at least one deflection current. As a result a correction quadripolar field is produced. The correction current generator includes passive elements, namely impedances, diodes and transistors operating as switches. The deflection coil halves are toroidally wound on the core.

COLOUR TELEVISION DISPLAY APPARATUS PROVIDED WITH A CATHODE-RAY TUBE

The invention relates to colour television display apparatus provided with a cathode-ray tube including a display screen and a system of deflection coils comprising a magnetic core on which a first and a second deflection coil unit are provided, each unit comprising two preferably symmetrical coil halves, said system of deflection coils being slid on the neck of the cathode-ray tube for deflecting in two substantially orthogonal directions at least one electron beam generated in the cathode-ray tube because a deflection current originating from a deflection current generator flows through each coil half, while for correction of the isotropic astigmatism a quadripolar field is generated approximately at the area of the deflection plane of the electron beam, the intensity of said field being substantially a square function of the instantaneous intensity of at least one of the deflection currents, the apparatus furthermore comprising a correction current generator for providing a correction current for generating the said quadripolar field.

Such apparatus is described in U.S. Pat. application No. 52,640, filed July 6, 1970. In this apparatus the deflection coil system is provided with at least four toroid auxiliary windings through which the correction current flows which is generated by a generator. This generator must apply sawtooth and parabolic signals to the said windings and includes active amplifier elements, namely transistors to which supply power is to be applied.

The relevant invention has for its object to provide improved and simplified apparatus in which substantially no supply power is required. To this end the apparatus according to the invention is characterized in that the correction current generator consists of passive elements, the correction current flowing through the coil halves of at least one deflection coil unit and the deflection coil halves being toroidally wound on the core.

Since the correction current generator consists of passive elements, the deflection current must flow through these elements so that the correction current is superimposed on the deflection current.

It may be noted that it is known per se from U.S. Pat. Specification No. 3,440,483 to cause a correction current for generating a quadripolar field to flow through deflection coils. The point there is, however, a correction of anisotropic astigmatic deflection errors so that the correction current is dependent on the product of the instantaneous intensity of the two deflection currents which in addition necessitates a modulator.

It is also known per se from German Pat. application 1,514,896 to eliminate astigmatic errors by means of passive elements. These elements are, however, used to render the field generated by one deflection coil unit dependent on the field generated by the other deflection coil unit. Otherwise the point is the deflection fields themselves and not correction fields while the said dependency is established by means of separate auxiliary windings on the core.

Some possible embodiments of display apparatus according to the invention will be described in detail by way of example with reference to the accompanying Figures in which:

FIG. 1 shows display apparatus provided with a three gun cathode-ray tube and switching means for supplying the correction current,

FIG. 2 shows an embodiment of the said switching means,

FIG. 3 shows characteristic curves of part of the embodiment according to FIG. 2, and

FIGS. 4, 5, 6, 7 and 8 show further embodiments of the said switching means.

10 In FIG. 1, 1 denotes an aerial by which the colour television signal can be received. This colour television signal is applied to an RF and IF amplifier 2 which amplifies the signal, detects it and subsequently applies it to a video amplifier 3. This video amplifier 3 applies the actual video signal consisting of a luminance signal and colour difference signals to a first output 4. These signals are processed in a matrix circuit 5 so that the three colour signals R, G and B become available at the output of this matrix circuit and are applied to the three cathodes K_R, K_G and K_B of the cathode-ray tube 6 operating as a colour television display tube. This tube 6 may be of the shadow-mask type and the colour image is displayed on its screen. The synchronizing signal, which is applied at one end to the line deflection generator 8 and at the other end to the field deflection generator 9, is derived from a second output 7 of video amplifier 3. Two output terminals 10 and 11 of generator 8 at one end are connected to the deflection coil system 12 and an output terminal 13 at the other end is connected to the final anode of display tube 6 for the supply of the final anode voltage of approximately 25 kilovolts. The output terminals 14 and 15 of field deflection generator 9 are likewise connected to deflection coil system 12 for the supply of the field deflection current. As a rule the line deflection current derived from output terminals 10 and 11, combined with a deflection unit of deflection coil system 12 ensures the deflection of the electron beams generated by the three cathodes 30 K_R, K_G and K_B in the horizontal direction. Simultaneously the field deflection current derived from output terminals 14 and 15, in co-operation with a further deflection unit of deflection coil system 12, ensures the deflection of the three electron beams in the vertical direction.

According to one aspect of the invention output terminals 10 and 11 and 14 and 15 are not directly connected to deflection coil system 12, but through arrangements 16 and 16', respectively. FIG. 2 shows an embodiment of arrangement 16. Windings 17 and 18 are the coil halves of the first-mentioned deflection unit, i.e. for the horizontal deflection. Arrangement 16 includes two impedances Z₁ and Z₂ each of which is arranged in series with one of the said windings. Line deflection generator 8 applies the line deflection current i_H to the circuit according to FIG. 2. When E_H is referred to as the voltage between outputs 10 and 11, and when Z_H is the impedance of both winding 17 and winding 18 and Z_M is the mutual impedance between windings 17 and 18, then:

$$E_H = [(Z_1 + Z_H)(Z_2 + Z_H) - Z^2_M]/2Z_H + Z_1 + Z_2 + 2Z_M i_H$$

65 In fact, impedance Z_M is to be considered as negative because the fields generated by the currents flowing in windings 17 and 18 support each other in the space within the core and therefore have opposite directions

in the core. This applies to toroidally wound windings. When the condition is imposed that:

$$Z_1 = Z_o - \Delta Z$$

$$Z_2 = Z_o + \Delta Z,$$

the first formula becomes

$$E_H = [(Z_o + Z_H)^2 - (\Delta Z)^2 - Z_M^2]/2(Z_o + Z_H + Z_M) i_H.$$

A current flows through winding 17:

$$i_1 = Z_o + Z_H + Z_M + \Delta Z / [(Z_o + Z_H) - Z_M^2 - (\Delta Z)] E_H$$

and a current flows through winding 18:

$$i_2 = Z_o + Z_H + Z_M - \Delta Z / [(Z_o + Z_H)^2 - Z_M^2 - (\Delta Z)^2] E_H.$$

If it is assumed for the sake of simplicity that $(\Delta Z)^2$ is negligibly small relative to $(Z_o + Z_H)^2 - Z_M^2$, we can write:

$$i_1 \approx [1/Z_o + Z_H - Z_M + \Delta Z / (Z_o + Z_H)^2 - Z_M^2] E_H \approx i_H/2 + \Delta i_H$$

and

$$i_2 \approx [1/Z_o + Z_H - Z_M - \Delta Z / (Z_o + Z_H)^2 - Z_M^2] E_H \approx i_H/2 - \Delta i_H,$$

in which

$$\Delta i_H = \Delta Z / (Z_o + Z_H)^2 - Z_M^2 \quad E_H \approx \Delta Z / 2(Z_o + Z_H + Z_M) i_H.$$

When impedance ΔZ varies proportionally to current i_H , it is found that current Δi_H is proportional to the square of current i_H . Under these circumstances windings 17 and 18 not only generate the magnetic field for the horizontal deflection but also a quadripolar field. According to a further aspect of the invention the deflection coils must be toroidally wound on the core of deflection coil system 12 with the deflection coil halves being located symmetrically relative to the vertical deflection direction. The result is that the poles of the quadripolar field are located substantially in the direction of the diagonals of the angle constituted by the horizontal and vertical deflection directions. As is further described in Netherlands Pat. application 6910495 the described apparatus is therefore suitable to correct isotropic astigmatic deflection errors which have been caused by deflection coil system 12 upon deflection in the horizontal direction.

It is found from the above-mentioned formula that current Δi is many times smaller than current i_H , so that the generated correction quadripolar field has a low intensity. An increase thereof is, however, obtained if a second quadripolar field is generated by a current flowing through the field deflection coils which is induced by current Δi , while the total induced voltage is zero. All this has been described in greater detail in U.S. Pat. application No. 294,912, Oct. 4, 1972 which also states that toroidally wound deflection coils are advantageous for this purpose.

Impedances Z_1 and Z_2 for which there applies that $Z_1 = Z_o - \Delta Z$ and $Z_2 = Z_o + \Delta Z$ while ΔZ is proportional to the current flowing through the impedances may be formed as coils having a saturable core. FIG. 3a shows the BH characteristic curve of the material of which this core is made in which B = the magnetic induction and H is the magnetic field strength. FIG. 3b shows the μH characteristic curve thereof in which $\mu = dB/dH$ is the permeability. At a field strength H_o and $-H_o$ the material is saturated while for a deviation $\pm \Delta H$ about field strengths H_o and $-H_o$ the BH characteristic curve

has a substantially square variation. It follows that the μH characteristic curve for the same deviation about field strengths H_o and $-H_o$ has a substantially linear variation. When the field strength varies from the value H_o

5 to the value $H_o + \Delta H$, the permeability varies in a linear manner from a value μ_o to a value $\mu_o - \Delta \mu$, while a variation of the field strength from the value $-H_o$ to the value $-H_o + \Delta H$ results in a linear variation of the permeability from the value μ_o to the value $\mu_o + \Delta \mu$. Since 10 field strength H is proportional to current i_H and since the impedance of the coil is proportional to its inductance and therefore to the permeability of the core, such a coil is indeed suitable for the envisaged purpose. Field strengths H_o and $-H_o$ may be adjusted by means 15 of two permanent rotatable magnets in the absence of current i_H . Alternatively the arrangement diagrammatically shown in FIG. 4 may be used with two cores 19 and 20 whose primary windings constitute the impedances Z_1 and Z_2 while a direct current I flows through 20 secondary windings 21 and 22, which current is adjustable by means of a battery 23 and a variable resistor 24. FIG. 4 shows that current I provides a positive premagnetisation for one of the cores 19 and 20 and a negative premagnetisation for the other core.

25 The latter arrangement is not usable in combination with the deflection coils for the vertical deflection because these coils are predominantly resistive for the field frequency. FIG. 5 shows another embodiment of circuits 16 and 16' of FIG. 1 in which in this embodiment the vertical deflection is corrected. Deflection generator 9 supplies the field deflection current i_V . Circuit 16' includes two diodes D_1 and D_2 and an impedance Z which are arranged as shown in FIG. 5. When the diodes are considered as ideal switches it can be assumed that one diode conducts during one half of the sweep of the sawtooth deflection current and then constitutes a short circuit while the other diode is blocked. During the other half of the sweep the reverse situation occurs. Therefore the deflection current always flows 40 through impedance Z .

When Z_V is the impedance of both winding 25 and winding 26, which constitute the coil halves of the deflection unit for the vertical deflection and when Z'_M is the mutual impedance therebetween, a current flows 45 through winding 25:

$$i'_1 = (Z_V + Z'_M / 2Z_V + Z + 2Z'_M) i_V$$

and a current flows through winding 26: $i'_2 = (Z_V + Z + Z'_M / 2Z_V + Z + 2Z'_M) i_V$ 50 when diode D_2 conducts.

This may be expressed as follows:

$$i'_1 = i_V/2 - \Delta i_V$$

$$i'_2 = i_V/2 + \Delta i_V$$

55 in which $i_V = \frac{1}{2} \cdot (Z/2Z_V + Z + 2Z'_M) i_V = k i_V$, that is to say, Δi_V is proportional to i_V .

Under these circumstances the deflection coil halves 60 not only generate the deflection field but also a quadripolar field whose pole axes are located approximately in the same manner as was the case for the arrangement according to FIG. 2, provided that the deflection coils are toroidally wound and are placed symmetrically relative to the horizontal and/or vertical deflection directions. The field strength thereof is proportional to the deflection current and can therefore be represented as a symmetrical triangle as a function of time, which may be considered as an approximation of a parabola. The 65

described arrangement is therefore suitable to correct isotropic astigmatic deflection errors which are caused by the deflection system 12 in the direction corresponding to the relevant deflection coil halves.

If the arrangement according to FIG. 5 relates to the horizontal deflection, coil halves 17 and 18 have an impedance $Z_H = R_H + j\omega L_H$, in which R_H and L_H are the resistance and the inductive part, respectively, of impedance Z_H . Since the proportionality constant k is a real number, impedance Z must be equal to $Z = R + j\omega L$ with $L/R \approx L_H/R_H$ while the choice of the absolute value of k depends on the desired slope of the mentioned triangular function. For the vertical deflection coil halves 25 and 26 are predominantly resistive so that impedance Z must be a predominantly resistive impedance.

FIG. 6 shows a refinement of the arrangement according to FIG. 5 in which diodes D_1 and D_2 are replaced by two transistors T_1 and T_2 of opposite types. These transistors do not operate as amplifiers but as switches and are either saturated or cut off while the conducting and cut-off periods are adjustable by means of two supply voltages $+V_{b1}$ and $-V_{b2}$ and two base resistors so that their function is the same as that of diodes D_1 and D_2 of FIG. 5 and, likewise as these diodes, may be considered as passive elements. The adjustment of transistors T_1 and T_2 may be such that the two transistors conduct about the centre of the sweep so that the field strength of the correction quadripolar field as a function of time is trapezoid-shaped, which is a better approximation of the desired parabola shape. Transistors have the additional advantage that the voltage drop thereacross in case of saturation is lower than in diodes.

FIG. 7 shows a modification of the apparatus according to the invention in which the deflection coil halves are arranged in series. Winding 27 is a secondary winding of an output transformer associated with deflection generators 8 and 9. Two preferably identical series arrangements of diodes D'_1 and D'_2 and of an impedance Z' are arranged between the junction N of deflection coil halves 17 and 18 and 25 and 26, respectively, and two taps P_1 and P_2 which are located symmetrically relative to the central tap M of winding 27. Diodes D'_1 and D'_2 may be replaced by transistors in a corresponding manner as described hereinbefore. Central tap M conveys the same potential as point N so that one diode conducts while the other is blocked. Also in this case it can be shown that the current flowing through one coil half is the sum of the deflection current and a current proportional to the deflection current and that the current flowing through the other coil half is the difference between the deflection current and the same current. This is the same situation as in the arrangement according to FIG. 5 and it has the same result in so far as the construction of impedance Z' is concerned.

FIG. 8 shows a complete diagram of the apparatus according to the invention in which a circuit according to that of FIG. 2 is used for the horizontal deflection and a circuit according to that of FIG. 5 is used for the vertical deflection. As a result a correction of isotropic astigmatic errors in the two deflection directions is obtained. An important improvement is obtained in that a second quadripolar field is generated by a current induced in the second deflection unit by a correction current flowing in the first deflection unit, while the total induced voltage is zero as described in the above-

mentioned U.S. Pat. application No. 294,912. Capacitor 28 has a low impedance for the line frequency and a high impedance for the field frequency and provides for decoupling between generators 8 and 9. Resistor 29

5 may be adjusted so as to eliminate a possible unbalance between the upper and lower portions of the image displayed on the screen of display tube 6. In a corresponding manner a coil 30 eliminates a possible unbalance between the right and left-hand portions of the image.

10 What is claimed is:

15 1. A circuit for a system of deflection coils comprising a magnetic core, first and second deflection units, each unit comprising two coil halves toroidally wound on said core, said circuit comprising a pair of deflection current generator means for generating two substantially linear deflection currents, means coupling said generator means to said units respectively; and means for correcting isotropic astigmatism comprising means for generating a quadripolar field having an intensity that is substantially a square function of one of the deflection currents, said quadripolar generating means comprising a passive element correction current generator means, and means for coupling said passive correction means to at least one deflection coil unit for providing a correction current through the halves thereof.

20 2. A circuit as claimed in claim 1 wherein one of said units comprises a horizontal deflection unit, said correction generator means comprising a pair of equal inductance saturable coils having magnetic fields of opposite directions in the absence of the horizontal deflection current, said saturable coils being series coupled to said horizontal coil halves respectively whereby series circuits are formed, said series circuits being parallel coupled together.

25 3. A circuit as claimed in claim 1 wherein said correction generator means comprises a pair of unidirectional conducting elements series coupled to said halves of one of said units respectively, whereby two series circuits and a pair of junctions between said elements and halves are formed respectively, said series circuits being parallel coupled together, said elements having opposite conductivity directions, and an impedance means coupled between said junctions.

30 4. A circuit as claimed in claim 1 wherein at least two of said halves are series coupled together, whereby a series arrangement having a junction is formed, and said correction generator means comprises a winding coupled to said series arrangement and having a pair of taps symmetrical relative to the center of said winding, a pair of series circuits each comprising of a unidirectional conducting element and an impedance means series coupled thereto, said series circuits being coupled between said junction and said taps respectively.

35 5. A circuit as claimed in claim 4 wherein each of said elements comprises an adjustable conducting period transistor.

60 6. A circuit as claimed in claim 3 wherein each of said elements comprises an adjustable conducting period transistor.

65 7. A circuit as claimed in claim 4 wherein each of said coil halves have resistance and reactance and said impedance means comprises an inductor having resistance and reactance in a ratio substantially equal to the corresponding ratio in said halves.

8. A circuit as claimed in claim 3 wherein each of said coil halves having resistance and reactance and said impedance means comprises an inductor having resistance and reactance in a ratio substantially equal to the corresponding ratio in said halves.

5

9. A circuit as claimed in claim 1 further comprising said deflection units.

10. A circuit as claimed in claim 9 wherein said coil halves are symmetrical.
